W. G. GIBBINS, DEC'D.
H. GIBBINS, EXECUTOR.
FLESHER MACHINE,
APPLICATION FILED AUG. 21, 1916.

Patented Feb. 19, 1918.

UNITED STATES PATENT OFFICE.

WILLIAM G. GIBBINS, OF ST. LOUIS, MISSOURI; HENRY GIBBINS EXECUTOR OF SAID
WILLIAM G. GIBBONS, DECEASED.

FLESHER-MACHINE.

1,256,892.

Specification of Letters Patent. Patented Feb. 19, 1918.

Application filed August 21, 1916. Serial No. 116,001.

To all whom it may concern:

Be it known that I, WILLIAM G. GIBBINS, a subject of the King of Great Britain, and a resident of the city of St. Louis, State of Missouri, have invented certain new and useful Improvements in Flesher-Machines, of which the following is a full, clear, and exact description, reference being had to the accompanying drawings, forming a part of this specification.

My invention relates to a flesher machine adapted for use in removing superfluous flesh, etc., from animal skins.

My invention has for its object to provide means permitting the accurate adjustment of guards relative to the cutting edges of rotary flesher knives, and to different positions around the axes of the knives so that skins to be fleshed may be presented to the knives in the most satisfactory manner by all operators.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a side elevation of a flesher machine constructed in accordance with my invention.

Fig. II is a vertical section, partly in elevation.

Fig. III is a fragmentary side elevation showing the side opposite to that shown in Fig. I.

Fig. IV is a fragmentary horizontal section taken approximately on the line IV-IV, Fig. I.

A designates a supporting frame provided with a pair of projecting bearing members 1. A shaft member 2, arranged between the side members of the frame A, is rotatably supported by the points of a pair of screws 3 (Fig. II).

The flesher knife B comprises a circular body 4 having its outer marginal portion turned laterally, at an obtuse angle, to form an outwardly flaring annular blade 5. The knife is preferably made of thin metal reinforced by stiffening disks 6 and 7 between

which the body portion 4 of the knife is clamped. 8 designates a drive pulley (Fig. II) formed integral with the disk 7 and secured to the rotatable shaft 2 by means of a set screw 9.

A segmental side guard C comprises a guard member 10 having an arcuate outer edge which lies adjacent to the cutting edge of the flaring blade. The outer edge of the guard member 10 is cut away at 11 to expose a portion of the blade, as shown in Fig. I. A collar 12, surrounding one of the bearing members 1, has a segmental flange 13 which is secured to the segmental guard member by means of screws 14 and 15. 70 Yieldable material 16, such as leather or rubber, is interposed between the segmental guard member 10 and the segmental flange 13. The guard member 10 may be accurately adjusted toward or away from the cutting edge of the knife, by tightening or loosening the screw 14, the interposed material 16 being free to yield in response to such movements.

I will now describe the universal guard 80 support, which allows the guard C to be adjusted around the axis of the knife, toward and away from said axis, and in a direction parallel with said axis. An eccentric ring 17, rotatably mounted on one of the bearing 85 members 1, is surrounded by the collar 12 which forms part of the guard C. A lug 18 extending from the eccentric ring is adapted to receive a tool for turning the eccentric ring on the bearing member 1. 90

The eccentric ring may be turned in either direction for the purpose of adjusting the segmental guard member 10 toward and away from the axis of the rotary knife. The collar 12 may be shifted on the eccentric, 95 in a direction parallel with the axis of the rotary knife, with the result of moving the segmental guard member in a corresponding direction. These adjustments allow the guard member to be accurately located in 100 any desired position with respect to the cutting edge of the knife. Furthermore, the collar 12 may be turned on the eccentric for the purpose of moving the guard member around the axis of the knife, and the same 105 result may be obtained by turning the collar 12 and the eccentric on the bearing member 1. This allows the guard member to be adjusted to various positions near the circular path of the cutting edge, the object being to 110

enable different operators to perform the fleshing operations at different points on the circle, so that each operator may adjust the device to a position that will enable him 5 to obtain the most satisfactory results.

After the guard C has been adjusted to the desired position it may be securely held by tightening a set screw 20 (Fig. I) to secure the collar 12 to the eccentric ring 17, 10 and then tightening the screw 21 to firmly force the eccentric ring into frictional engagement with the frame A.

A flaring peripheral guard member 10, associated with the guard member 10', is secured to a flange 13' on a collar 12' the latter being fitted to an eccentric ring 17' on a bearing member 1. These elements constitute an adjustable support for the guard member 10', and since they are constructed 20 and arranged in the same manner as the means for supporting the guard member 10, a further description of the various adjustments is deemed unnecessary.

The means for sharpening the flaring 25 blade comprises a pair of sharpening rods 22 each of which is slidably mounted in a bearing 23 and provided with a sharpening head 24 adapted to engage the blade. Each bearing 23 is pivotally connected to the 30 frame A to allow the sharpener to move toward and away from the cutting edge of the blade. It will be observed that the sharpening heads 24 lie at opposite sides of the blade, and that they may be forced into engagement with the blade and reciprocated transversely of the blade while the rotary 35 knife is in motion.

The skin is pulled firmly along the arcuate 40 faces of the guards 10 and 10' while it is exposed to the cutting edge of the flaring blade 5. It is necessary to pull the skin firmly for the purpose of stretching it at the cutting edge, the object being to stretch the skin uniformly in all directions at this point. The 45 guards 10 and 10' are arranged at an acute angle to each other, thus allowing the skin to stretch circumferentially of the cutting edge in response to the pulling action whereby the skin is forced onto and drawn across the 50 guards. If the guards 10 and 10' were arranged at an obtuse angle or at a right angle to each other (as they would necessarily be if associated with a cylindrical knife) the

same desirable stretching action could not be obtained, and for this reason it is generally recognized that a satisfactory stretching action cannot be accomplished by fleshing machines having cylindrical knives. However, by flaring the annular blade 5 as herein shown, its plain cutting edge will be properly presented to the skin, and the guards can be arranged at an acute angle to each other to provide for the desired stretching action.

I claim:

1. In a fleshing machine, a rotary fleshing knife, a guard located adjacent to said rotary knife, and a universal support for said guard, said universal support being adjustable to allow said guard to move toward and away from the axis of the knife, around said axis and in a direction substantially parallel with said axis.

2. In a fleshing machine, a fleshing knife, a guard adjacent to the cutting edge of said knife, an eccentric for adjusting said guard to change its position with respect to said cutting edge, and means for securing said guard and eccentric.

3. In a fleshing machine, a rotary fleshing 80 knife, a guard adjacent to the cutting edge of said rotary knife, an eccentric ring surrounding the axis of said rotary knife, said guard being fitted to said eccentric ring and the latter being adjustable to move the guard 85 toward and away from the axis of the knife.

4. In a fleshing machine, a fleshing knife, a guard located adjacent to the cutting edge of said knife, said guard being provided with a collar, an eccentric surrounded by and 90 fitted to said collar, a bearing to which said eccentric is rotatably fitted, said eccentric being adjustable to change the position of said guard with respect to the cutting edge of said fleshing knife, and means for securing 95 said guard.

5. In a fleshing machine, a fleshing knife, a guard member adjacent to the cutting edge of said knife, a support for said guard member, yieldable material between said guard member and its support, and an adjustable fastening device securing said guard member to its support, said fastening device being adapted to compress said yieldable material so as to adjust the guard member.

WILLIAM G. GIBBINS.
